LUBRICANT-DISPENSING APPARATUS

Russell J. Gray, Meadeville, Minn., assignor to
Gray Company, Inc., Minneapolis, Minn., a cor-
poration of Minnesota

Application February 2, 1949, Serial No. 619

Term of patent 7 years

(Cl. D52—2)

To all whom it may concern:

Be it known that I, Russell J. Gray, a citizen of the United States and residing at Meadeville, in the county of Hennepin, State of Minnesota, have invented a new, original, and ornamental Design for Lubricant-Dispensing Apparatus, of which the following is a specification, reference being had to the accompanying drawing, forming part thereof.

Figure 1 represents a perspective view of a lubricant-dispensing apparatus, showing my new design, the container and hose being shown in broken lines for illustrative purposes only.

Figure 2 represents a top plan view of the embodiment of Figure 1.

Figure 3 represents a side elevational view of the embodiment of Figures 1 and 2.

Figure 4 represents a bottom plan view of the embodiments of Figures 1, 2 and 3.

The characteristic features of my design reside in the portion shown in full lines.

I claim:

The ornamental design for a lubricant-dispensing apparatus, as shown and described.

RUSSELL J. GRAY.
